[57] CLAIM

The ornamental design for a ladies' rotary shaver, as shown and described.

DESCRIPTION

FIG. 1 is a perspective view of the ladies' rotary shaver showing my new design;
FIG. 2 is a top plan view thereof;
FIG. 3 is a front elevational view thereof;
FIG. 4 is a side elevational view, looking from the right side of FIG. 3;
FIG. 5 is a side elevational view, looking from the left side of FIG. 3;
FIG. 6 is a rear elevational view thereof;
FIG. 7 is a bottom plan view thereof;
FIG. 8 is a front elevational view of an alternate embodiment of the ladies' rotary shaver showing my new design;
FIG. 9 is a side elevational view, looking from the right side of FIG. 8;
FIG. 10 is a side elevational view, looking from the left side of FIG. 8;
FIG. 11 is a rear elevational view thereof; and,
FIG. 12 is a bottom plan view thereof.
